Primary Examiner — Carol P Rademaker

(57) **CLAIM**

The ornamental design for a bottle, as shown and described.

DESCRIPTION

FIG. 1 is a top, front, right side perspective view of a first embodiment of a bottle;

FIG. 2 is a front elevational view thereof, the rear elevational view being identical except for the unclaimed threads;

FIG. 3 is a right side elevational view thereof, the left side elevational view being identical except for the unclaimed threads;

FIG. 4 is a top plan view thereof;

FIG. 5 is a bottom plan view thereof;

FIG. 6 is a top, front, right side perspective view of a second embodiment of a bottle;

FIG. 7 is a front elevational view thereof, the rear elevational view being identical except for the unclaimed threads;

FIG. 8 is a right side elevational view thereof, the left side elevational view being identical except for the unclaimed threads;

FIG. 9 is a top plan view thereof; and,

FIG. 10 is a bottom plan view thereof.

The broken lines shown in the drawing views are included for the purpose of illustrating environmental structure and form no part of the claimed design.

1 Claim, 6 Drawing Sheets
